FURNACE UNIT

Frank F. Jackson, Cleveland, Ohio

Application June 30, 1934, Serial No. 733,262

1 Claim. (Cl. 263—6)

This invention relates as indicated to furnace units and more particularly to the construction of a work-conveying roll adapted for use in metallurgical furnaces such as normalizing furnaces, etc.

More particularly, my invention relates to the construction of a so-called dry roll, i. e., a roll which is journaled in stationary bearings on opposite sides of the furnace, extending through the furnace to movably support work thereon and not being provided with means for circulating a cooling medium such as water therethrough.

A certain amount of difficulty has been experienced in the past with conveyor rolls of this type, particularly due to the fact that the central portions of such rollers are at all times subjected to the intense heat of the furnace and no means is provided whereby the same are internally cooled.

Due particularly to the width of the furnaces, i. e., the length of that portion of the rolls subjected to the intense heat of the furnace, rolls of this character usually fail in their central portions long before the terminal portions are worn out.

It is among the objects of my invention to provide conveyor rolls for metallurgical furnaces characterized by the provision of a central section joined to terminal sections in a particular manner so that the central sections may be readily replaced after failure and so that the terminal portions may be used until worn out and the operating cost of such rolls consequently materially reduced.

It is a further object of my invention to provide a work supporting roll for furnaces of the above described character wherein the central section is so secured to the terminal sections that the central sections may be readily replaced while at the same time maintaining a sufficiently structurally sound connection between the central and terminal portions so as to in no way interfere with the operation of the roll.

It is a further object of my invention to provide a roll of the character described in which the central section is formed from a centrifugal casting; thus making possible the utilization of a structure which is superior to any previously available.

Other objects of my invention will appear as the description proceeds.

To the accomplishment of the foregoing and related ends, said invention, then, consists of the means hereinafter fully described and par-

ticularly pointed out in the claim; the annexed drawing and the following description setting forth in detail certain structure embodying the invention, such disclosed means constituting, however, but one of various structural forms in which the principle of the invention may be used:

In said annexed drawing:—

Fig. 1 is a fragmentary transverse sectional view of a metallurgical furnace showing a conveyor roll constructed in accordance with the principles of my invention associated therewith; Fig. 2 is a fragmentary sectional view drawn to an enlarged scale of a portion of the roll illustrated in the previous figure showing particularly the mode of connection between the central and terminal sections of the roll; Fig. 3 is a transverse sectional view of the roll as illustrated in Fig. 2 taken on a plane substantially indicated by the line 3—3; and Fig. 4 is a fragmentary developed view of one terminal portion of the central section of the roller illustrated in the previous figures.

Referring now more specifically to the drawing and more especially to Fig. 1, the furnace unit or conveyor roll comprising my invention is shown associated with a metallurgical furnace such as a normalizing furnace generally indicated at 1. The furnace 1 is shown as provided with the usual side walls 2 through which extend openings 3 arranged to receive the roll comprising my invention. Suitable frame work such as generally indicated at 4 is provided on opposite sides of the furnace on which are mounted bearing blocks generally indicated at 5 in which the journals of the roll rotate. The roll generally indicated at 6 extends as at 7 through one of the bearings 5 and has some means such as a sprocket 8 secured thereto and by which the same may be driven.

As previously indicated, my invention pertains particularly to the construction of a roll comprising a plurality of sections which are assembled in a particular manner to form a composite structure characterized by the fact that the central portion thereof may be renewed after failure.

As illustrated in Fig. 1, the terminal portions 9 and 10 of the roll are, inwardly of their journal portions, flared so as to provide a relatively large diameter to which the central section may be conveniently secured. The central section generally indicated at 11 is preferably in the form of a cylinder. The inner ends of the terminal sections 9 and 10 are provided with reduced cylindrical extensions 12 having an outside diameter substantially equal to the inside diameter of the

terminals of the central section 11. A shoulder generally indicated at 13 is provided on the terminal sections for the purpose hereinafter more fully explained.

5 As most clearly illustrated in Figs. 2 to 4 the terminal portions of the intersection 11 are provided with a plurality of spaced staggered rows of openings 14 extending therethrough. After the parts have been assembled into the position 10 illustrated in Fig. 1, weld metal, preferably of some heat resistant composition, is deposited in the openings 14, keying the central and terminal sections securely together.

15 The preferred mode of assembling the central and terminal sections may be as follows:— The central section without the openings 14 in the terminal portions thereof is telescopically engaged with the cylindrical projections 12 of the terminal sections 9 and 10 until the ends of 20 the central section abut the shoulders 13 on the terminal sections. After the parts have been brought into such assembled relation, the openings 14 are drilled in the central section; the points of the drill forming such holes penetrating 25 for a short distance into the cylindrical extensions on the terminal sections. After such drill holes are formed, the same are filled with weld metal in the manner hereinbefore explained, such weld metal filling the shallow openings formed 30 in the terminal sections by the points of the drills, thereby insuring a more positive connection between the several sections of the roll.

35 A plurality of annular work supporting members generally indicated at 15 are secured in axially spaced relation on the central portion of the roll.

40 Should a roll fail due to a deterioration of the central section thereof, such roll may be repaired by inserting a new central section by the following procedure:—

45 The central section will be sawed off adjacent the inner ends of the terminal sections; the terminal sections will then be placed in a lathe and the terminal portion with the central section remaining on the terminal sections will be turned down by the usual lathe operation. In order to facilitate the supporting of the terminal sections in the lathe for this turning down operation, such sections are provided with a transversely extending 50 bar or brace generally indicated at 16 which may, at an axis of the section, be provided with an opening or recess to be engaged by the head or tail stock of the lathe.

55 After the terminal sections have been thus turned down to substantially their original size and shape, a new central section may be assembled therewith and united thereto in the manner heretofore explained.

60 As previously indicated, the central section is preferably formed from a centrifugal casting. The assembly of a composite roll from a plurality of elements in accordance with the principles of my invention makes possible the use of a centrifugal casting in the center section of the roll

which is not possible when the entire roll is made in one piece. Use of a centrifugal casting in the central section is advantageous for the reason that it is possible to maintain closer tolerance in a centrifugal casting than in the common form 5 of casting and furthermore, the structural strength of a thin-walled centrifugal casting of this character is believed to be superior to that of the usual type casting. The possibility of maintaining closer tolerance in a centrifugal casting 10 enables me to form the central section with a uniform wall section which is relatively thin. This is a particular advantage when it is remembered that rolls of this character fail primarily due to their own weight, rather than due to the 15 weight of the material supported thereon. It is advantageous, therefore, to form the wall of the central section as thin as possible in order to reduce the weight but not too thin in order that weak sections may occur. It is to the solution 20 of this last named problem that a centrifugal casting for the central section is particularly applicable and the use of the centrifugal casting in the central section is made possible only by the assembly of a plurality of elements to form a 25 complete roll.

25 The telescopic engagement of the parts at the juncture between the central and terminal sections of the roll produces a very strong, highly 30 efficient joint between the parts, one which does not rely upon auxiliary connecting means such as keys and bolts to carry the stress to which the roll is subjected, and a connection which is particularly applicable to the replacement of the 35 central section.

35 Other forms may be employed embodying the features of my invention instead of the one here explained, change being made in the form or construction, provided the elements stated by the following claim or the equivalent of such 40 stated elements be employed.

I, therefore, particularly point out and distinctly claim as my invention:—

45 A conveyor roll for furnaces comprising terminal sections respectively provided at their outer ends with journals by which the roll may be rotatably supported and at their inner ends with substantially cylindrical extensions, a radially and circumferentially extending abutment on each of said terminal sections at the 50 outer ends of said extensions, the face of said abutment lying in a plane normal to the axis of said journals, a central cylindrical section telescopically engaging said extensions and terminally engaging said abutment faces, said central 55 section and extensions provided with a plurality of circumferentially and axially spaced openings extending through the wall of said central section and partially through the wall of said extensions, and weld metal filling said openings and 60 securing together said central and terminal sections.

FRANK F. JACKSON.
